UNITED STATES PATENT OFFICE.

JAMES E. HAMILTON, OF TWO RIVERS, AND JULIUS HAMACHECK, OF MANITOWOC, WISCONSIN, ASSIGNORS TO THE HAMILTON MANUFACTURING COMPANY, OF TWO RIVERS, WISCONSIN, A CORPORATION OF WISCONSIN.

MACHINE FOR DRESSING BLOCKS OF WOOD TO THICKNESS.

No. 895,401.

Specification of Letters Patent.

Patented Aug. 4, 1908.

Application filed February 12, 1907. Serial No. 357,082.

To all whom it may concern:

Be it known that we, JAMES E. HAMILTON and JULIUS HAMACHECK, citizens of the United States, and residents of Two Rivers, 5 Manitowoc county, Wisconsin, and Manitowoc, Manitowoc county, Wisconsin, respectively, have invented certain new and useful Improvements in Machines for Dressing Blocks of Wood to Thickness, of which 10 the following is a specification.

This invention relates to machines for dressing blocks of wood to thickness and relates particularly to machines for dressing blocks to thickness which are to be used for 15 making what are known as "end-wood" type, said machine being commonly known as "type-high" machines.

A machine of the general type to which our invention relates, is shown and described 20 in U. S. Letters Patent No. 833,163, dated October 16, 1906.

Among the objects of the present invention are the following:—To provide an improved pressure device for applying pressure 25 to blocks of wood supported upon the carriage of the machine while being presented to the cutter, whereby pressure will be exerted thereon at points across the entire width thereof and closely adjacent to the cutter; 30 to provide for independently adjusting the pressure at any point; and to provide for entirely removing the pressure at any point; to provide an improved feed mechanism for the carriage whereby the feed will be automatically reversed when said carriage reaches 35 the rearward limit of its movement and said carriage returned and stopped at its forward or initial position; and to provide manually operated means for throwing in the feed 40 mechanism when it is desired to again advance said carriage; to provide an improved clamping dog for securing the blocks of wood upon the carriage, whereby setting up said dogs will operate to draw said blocks into 45 firm contact with the surface of the carriage; to provide improved means in connection with a circular cutter rotating in a plane parallel with the surface of the carriage for securing desired clearance at the rear side of 50 said cutter; and to provide an improved support for the machine frame, whereby it may readily accommodate itself to irregularities in the floor or foundation without springing said frame or stationary bed.

55 To effect the objects of our invention, our

improved machine comprises the various features, combinations of features and details of construction hereinafter described and claimed.

In the accompanying drawings, in which a machine of our invention is fully illustrated,—Figure 1 is a left hand side view of a machine of our invention, the pressure device being raised and a portion of the frame or fixed bed being broken away. Fig. 2 is a top plan view of our improved machine. Fig. 3 is an enlarged sectional elevation thereof on the line 3—3 of Fig. 1. Fig. 3^a is an exaggerated diagrammatic view to emphasize the dish of the bed and the tilt of the cutter. Fig. 4 is an enlarged sectional view of the cutter and cutter head. Figs. 5, 6, 7 and 8 are enlarged detail views of the pressure devices, Figs. 5 and 6 being similar sectional views showing the pressure roller in inoperative adjustment and operative adjustment, respectively. Figs. 9, 10 and 11 are enlarged views of the device for shifting the belts controlling the feed mechanism for the carriage, Fig. 9 being a sectional view substantially on the line 9—9 of Fig. 2. Figs. 12, 13 and 14 are enlarged detail views of the dogs for clamping the work to the carriage. Figs. 15 and 16 are enlarged detail views showing the dogs on the carriage which control the shifting mechanism for the feed belts; and Fig. 17 is a view similar to Fig. 16, showing the hinged portion of the rear dog swung rearwardly as the movement of the carriage is reversed at the rear end of its stroke.

As regards its general features, our improved machine may be of any usual or desired construction, comprising a stationary frame or bed A, a carriage B mounted in suitable guides thereon so as to be movable lengthwise thereof in both directions, a cutter head C, a cutter D secured thereto and a cutter arbor E.

The machine is shown as operating on a block of wood F, which is secured to the carriage B by suitable clamps or dogs.

To effect the object of our invention, as it relates to improved means for supporting the frame thereof, we employ, instead of four rigid legs, as heretofore, two rigid legs 1 at one end of the machine, as shown the rear end, and at the other or forward end of the machine a single centrally located leg comprising a section 2 rigidly secured to the bed or frame A and a base 3, adapted to be se-

90

95

100

105

110

cured to the floor or foundation, said base being provided in its upper surface with a rounded recess 4 adapted to receive the rounded lower end 5 of the upper section 2, 5 the curve of the recess 4 being of greater radius than the curve of the rounded lower end of the rigid section 2, thus providing for a rocking movement of said rigid section 2 in the base 3. The base 3 of said leg is secured 10 to the rigid section 2 thereof, so as to permit free relative movement thereof, by means of a bolt 6, the under side of the head of which is rounded and is adapted to engage a corresponding rounded socket 7 on said base 3. 15 The shank of said bolt extends through registering holes 8 in the sections 2 and 3 of said leg, said holes being somewhat larger than said bolt. Said bolt 6 is secured in position by means of a nut threaded to the end thereof, and desired flexibility is imparted to the 20 joint connecting the sections of said leg by means of a coiled spring 9 inserted between the end of the section 2 of the leg and a nut threaded to the end of said bolt. With this 25 construction, it is obvious that, while the bed or frame A of the machine will be rigidly supported, it will, at the same time, be free to adapt itself without springing to irregularities in the foundation, whether permanent or 30 temporary, thus insuring absolutely uniform work at all times.

To effect the object of our invention, as it relates to securing the desired clearance at the rear side of the cutter, the cutter arbor 35 E, instead of being set at right angles to the upper surface of the carriage B, is set at an angle, with its upper end slightly inclined towards the front end of the machine. With this construction, the front side or edge of 40 the cutter D will obviously be lower than the rear side or edge thereof, the difference in height depending upon the inclination of said cutter arbor E. In practice, a desirable relation is to adjust said cutter so that the front 45 edge thereof will be approximately 3/32 of an inch lower than the rear edge thereof.

To better illustrate the inclination of the cutter D, to provide the necessary clearance at the rear side thereof, and the corresponding 50 dish of the carriage, in order that the depressed front edge of the cutter shall run parallel with the dished transverse surface of said carriage, these features are shown on an enlarged and greatly exaggerated scale in 55 Figs. 3^a and 4. In Fig. 4, x represents the longitudinal surface line of the finished work.

In order that the depressed front edge or side of the cutter D will run parallel with the surface of the carriage B and thus dress the 60 blocks of wood F supported on said carriage to uniform thickness throughout the upper surface of the carriage is dished transversely, as clearly shown, on a somewhat exaggerated scale, at 10, Fig. 3.

65 In practice the necessary dish to the sur-

face of the carriage B can be secured or provided by fastening to the cutter head C a circular grinding wheel of the same diameter as the cutter D designed to be used on the machine. By then adjusting the cutter 70 arbor E at its designed operative inclination, rotating the arbor shaft and moving the carriage B back and forth beneath said cutter, until the grinding wheel has ground itself to a bearing entirely across said carriage, the 75 proper dish will be obtained, so that when the cutter D is secured to the cutter head C in place of the grinding wheel, its front side or edge will run parallel with the dished upper surface 10 of the carriage B and, when a 80 block F is secured upon the carriage B with its under surface conformed to the dish of said carriage, and is presented to said cutter, said cutter will operate to cut the same to uniform thickness throughout. 85

The bearings for the cutter arbor E are formed in a slide 11, see particularly Figs. 2 and 4, mounted so as to be movable towards and from the carriage D in suitable guides or ways formed in a head supported upon standards 12 rigidly secured to the bed or frame A of the machine.

To provide for adjusting and truing up the cutter arbor E relatively to the surface of the carriage B, the head carrying the slide 11, instead of being secured to the standards 12 in fixed adjustment, comprises members 13 and 14, of which the member 13 is pivoted at its lower end to said standards 12, by means of stud bolts 15, see Fig. 1, which form a transverse axis, so that the upper end of said member 13 may be swung either forwards or backwards about said stud bolts 15 as a pivot, and the member 14 is pivoted to the member 13 by means of a stud bolt 16 so that its upper end 105 may be swung transversely of the machine in either direction.

Our improved machine also comprises means for adjusting said members 13 and 14 pivotally and for securing the same in desired pivotal adjustment. In the preferable construction shown, said members 13 and 14 are adapted to be adjusted and secured in position in the following manner:

Inserted through suitable holes or openings 110 in said members 13 and 14 adjacent to their upper ends and preferably adjacent to opposite sides thereof, is a bolt 17, threaded to which are nuts 18 by means of which the member 14 may be rigidly clamped to the 120 member 13. To provide for adjusting the member 14 pivotally, the hole in the member 13, through which the bolt 17 passes, is elongated transversely about the stud bolt 16 as a center.

To provide for adjusting the member 13 pivotally, the bolts 17 are extended beyond the nuts 18, as shown at 19, the ends thereof passing freely through suitable holes or openings formed in a frame member 20 which 130

Planners,
Rotary Cutter,
Disk.

rigidly connects the standards 12 on opposite sides of the machine. As shown, also, the extensions 19 of the bolts 18 are reduced in size below the bottoms of the threads on said 5 bolts 17, and threaded thereto at opposite sides of the central web of the frame member 20 are nuts 21, by screwing up one or the other of which, the upper end of the member 13 may be swung in either direction, as desired.

10 The member 13 is adapted to be adjusted pivotally by means of thrust screws 22 which are threaded into rigid portions of the member 13, see Fig. 2, and the heads of which bear against opposite edges of the member 14.

15 The member 13 is adapted to be secured in fixed pivotal adjustment by means of bolts 23, see Figs. 1, 2 and 4, which pass through holes or openings in the standards 12 and are threaded into rigid portions of said members 20.

20 13. To provide for desired pivotal adjustment of said member 13, the holes in the standards 12, through which said clamping bolts 23 extend, are elongated, as best seen in Figs. 2 and 4.

25 The slide 11 on which the bearing for the cutter arbor is formed is adapted to be adjusted towards and from the carriage B by means of a screw 24, threaded to a nut 25 rigidly secured to said slide, said screw being 30 secured against longitudinal movement in a lug or flange 26 on the member 14 of the head carrying said slide 11. The upper end of the screw 25 is squared to receive a socket wrench.

35 The carriage B is adapted to be moved or fed lengthwise of the bed or frame A by means of a feed screw 27, see Figs. 1 and 2.

To effect the objects of our invention as it relates to an improved feed mechanism 40 whereby the feed will be automatically reversed when the carriage B reaches the rearward limit of its movement and returned and stopped at its extreme forward or initial position, the construction of our improved machine is as follows:

45 Revolvably mounted in suitable bearings at the rear end of the machine is a cross shaft 28, a miter gear secured to rotate with which meshes with a miter gear secured to rotate 50 with the feed shaft 27, see Figs. 1 and 2. Secured to the cross shaft 28 is a driving pulley 29 and revolvably mounted upon said shaft at opposite sides of said fast pulley 29 are loose pulleys 30 and 31. Two belts, one open and 55 the other crossed, are adapted to run on the loose pulleys 30 and 31 and to be shifted alternately to the tight pulley 29, thus through the medium of the miter gears secured to the cross shaft 28 and to the feed screw 27, operating 60 to rotate said feed screw in opposite directions and thus reverse the feed or travel of the carriage B. Extending over the pulleys 29, 30 and 31 is a bracket 32. Pivoted to the under side of said bracket 32 at 33 and 65 34, respectively, are shipping levers 35 and

36, through suitable guide openings in the end of which the driving belts pass. Mounted in suitable guide bearings on the upper side of the bracket 32 is a slide 37 formed in which are cam slots 38 and 39, respectively, which 70 are adapted to be engaged by suitable projections on the shipping levers 35 and 36. As shown, said projections consist of rollers 40 and 41 revolvably mounted on studs secured in said shipping levers 35 and 36, respectively. To provide for desired pivotal movement of the shipping levers 35 and 36, suitable slots 42 and 43 are formed in the bracket 32 through which the cam rollers 40 and 41 and the studs on which they are 75 mounted extend. As shown, the slots 42 and 43 are engaged by reduced downward extensions of the cam rollers 40 and 41.

The cam slots 38 and 39 comprise off-set straight portions 44 and 45 and 44¹ and 45¹, 80 respectively, which are connected by means of inclined sections 46 and 47 and 46¹ and 47¹, respectively.

The relation of parts is such that, when the cam roller 40 on the shipping lever 35 is in 90 engagement with the straight section 45 of the cam slot 38, the belt controlled by the shipping lever 35 will be shifted to the loose pulley 30 and when in engagement with the straight section 44 of said cam slot 38, that 95 said belt will be shifted to the tight pulley 29, the inclined sections 46 and 47 of said cam slot operating to guide said cam roller 40 from one straight section to the other of said cam slot, depending upon the direction of 100 movement of the slide 37. Likewise, the relation is such that, when the cam roller 41 is in engagement with the straight sections 45 of the cam slot 39, the belt controlled by the shipping lever 36 will be shifted to the tight 105 pulley 29 and when in engagement with the straight section 44¹ of the cam slot 39, said belt will be shifted to the loose pulley 31, the inclined sections 46¹ and 47¹ operating to 110 guide said cam roller from one of said straight sections to the other, depending upon the direction of movement of the slide 37.

The inclined sections 46, 47 and 46¹ are substantially parallel and are located in the same positions lengthwise of the slide 37. 115 The cam section 47¹, however, begins at a point rearward from the rear ends of sections 46, 46¹ and 47, so that when the slide 37 is moved rearwardly, the cam roller 41 will not come into contact therewith until the section 120 47 has brought the cam roller 40 into engagement with the straight section 45 of the cam slot 38 and thus shifted the belt controlled by the shipping lever 35 to the loose pulley 30. Thus, with the cam rollers 40 and 41 in 125 engagement, respectively, with the straight sections 45 and 45¹ of said cam slots, in which positions the belt controlled by the shipping lever 35 will be on the loose pulley 30 and the belt controlled by the shipping 130

lever 36 will be on the tight pulley 29, in which relation the feed screw will be rotated in the proper direction to feed the carriage B rearwardly under the cutter D. When movement is imparted to the slide 37 rearwardly, the inclined sections 46 and 46¹ of said cam slots will operate to move the shipping levers 35 and 36 pivotally, so as to shift the belts controlled thereby, respectively, to the fast pulley 29 and the loose pulley 31, which will operate in an obvious manner to reverse the direction of feed and to return the carriage B to its forward or initial position, in which direction it will continue to move until the slide 37 is again moved forwardly to cause the inclined section 47 of the cam slot 38 to engage the cam roller 40 and thus move the shipping lever 35 pivotally to shift the belt controlled thereby to the loose pulley 30, which will be effected by suitable mechanism when the carriage B reaches the forward limit of its movement or its initial position. As previously stated, however, the relation is such that the cam roller 41 will not come into contact with the inclined section 47¹ of its cam slot until after the cam roller 40 has passed into engagement with the straight section 45 of its cam slot. Thus, both belts will be running on the loose pulleys and the carriage B will come to rest and remain stationary until the shipping lever 36 is moved pivotally to cause the belt controlled thereby to run upon the tight pulley 29, which is designed to be done manually by suitable means in connection with the means for imparting movement to the slide 37.

A spring 48, see Fig. 9, operates to maintain the shipping lever 36 normally in position so that the belt controlled thereby will run on the loose pulley 31.

Movement is adapted to be imparted to the slide 37 to operate the shipping levers 35 and 36 by means of suitable operative connection with the carriage B, as follows:—

45 Revolubly mounted in a suitable bearing on the bracket 32 is a stub shaft 49 secured to the upper end of which is a gear 50 the teeth of which mesh with a rack 51 formed on the slide 37 and secured to the lower end of said stub shaft is a pinion 52 the teeth of which mesh with teeth formed on a rack bar 54, which, as shown, is rigidly secured to a rod 55 which is fitted to and longitudinally movable in suitable fixed bearings formed in bearing blocks or bosses 56 and 57 on the bed or frame of the machine. Rigidly secured adjacent to opposite ends of the carriage B, see particularly Figs. 2, 15 and 16, are dogs 58 and 59, which are adapted to strike stops 60 on the shipping rod 55 as the carriage B moves in opposite directions and to impart movement to said shipping rod and through the described connections to the cam slide 37 of the belt shipping device to either re-

verse the feed or to throw the feed out of 65 operation, as heretofore described. As shown, said stops consist of levers 60 and 61 pivoted to the bed or frame of the machine, formed in the upper ends of which are slots 62 and 63, through which the rod 55 extends, 70 said shipping rod 55 being connected to said stop levers by means of pins 64 secured in said shipping rod the ends of which engage slots 65 formed in said stop levers 60 and 61. The slots 62, 63 and 65 are sufficiently long 75 to permit necessary movement of the shipping rod 55.

In the preferable construction shown, the rear dog 59 comprises a plate 66 hinged or pivoted to the rear side thereof, so that the lower end thereof will be free to swing rearwardly, but will be held against forward pivotal movement by the end of said dog 59. The object of this construction is to provide for the plate 66 releasing itself from the stop 61 in case the momentum of the carriage should carry said plate over the end of the stop 61, which, with a rigid dog, would cause said dog and stop to wedge upon each other and possibly result in breaking one or both 90 thereof. The front dog 58 is substantially the same in construction as the rear dog 59, excepting that, as shown, it does not comprise the hinged plate 66, such plate not being necessary, for the reason that the parts 95 are so adjusted that the carriage will come to rest before said dog passes the stop 60. As previously explained, the relation is such that when the dog 59 strikes the stop 61, as the carriage B is fed rearwardly under the 100 cutter D, said dog will move the stop 61, and through it the rod 55 and the slide 37 a sufficient distance to disengage the cam rollers 40 and 41 on the shipping levers 35 and 36 from the sections 45 and 45¹ of the cam slots 38 105 and 39 and to bring them into engagement first with the inclined sections 46, 46¹ and then with the sections 44 and 44¹ thereof, thus reversing the feed and causing the carriage to move toward the front end of the 110 machine. As said carriage approaches its extreme forward or initial position, the dog 58 strikes the stop 60, the relation being such that said stop will be moved thereby a sufficient distance to cause the inclined section 47 115 of the cam slot 38 to engage the cam roller 40 and thus shift the belt controlled by the shipping lever 35 from the tight pulley 29 to the loose pulley 30. As previously stated, this will occur before the inclined section 47¹ of the cam slot 39 engages the cam roller 41 on the shipping lever 36. Both belts will thus be running on the loose pulleys, thus stopping the feed and allowing the carriage B to come to rest in its extreme forward or initial position in the manner desired.

When it is again desired to throw in the feed, the rod 55 is drawn forward by means

of a hand lever 67 on the front stop lever 60 a sufficient distance to cause the inclined sections 47¹ of the cam slot 39 to engage the cam roller 41, thereby moving the slipping lever 5 36 pivotally to shift the belt controlled thereby to the tight pulley 29, thus throwing in the feed. This cycle is repeated each time a new block to be dressed is placed upon the carriage B.

- 10 As regards the improved dogs for securing the blocks F upon the carriage B, the construction of the machine is as follows, see particularly Figs. 2, 12, 13 and 14. Formed in the upper surface of the carriage B are 15 transverse T-slots 68 fitted to which are the heads 69 of clamps 70. Said clamps 70 are arranged in pairs and are adjustable towards and from each other by means of screws 71, each of which comprises right and left hand 20 sections which are respectively threaded to correspondingly threaded holes or openings formed in the head 69 of each pair of clamps 70. The screws 71 are secured against longitudinal movement by means of yokes 72 25 secured to the carriage B which engage grooves 73 formed in said screws. The outer ends of said screws are squared to receive a wrench.

Formed on the portions of the clamps 70 30 which project above the surface of the carriage B, are inclined guideways 74 to which are fitted flanges 75 on jaws 76, said guideways 74 being outwardly and downwardly inclined and said jaws being shorter than the 35 height of the clamps 70 above the carriage B, so that, when said jaws 76 are subjected to an outward pressure they will be forced downwardly along the guides 74 towards the surface of the carriage B. Springs 77 inserted beneath the jaws 76 operate to maintain 40 said jaws 76 normally at the upward limit of their movement and plates 78 secured to the upper surface of the clamps 70 and which extend over portions of the jaws 45 76, limit the movement of said jaws under the influence of said springs. The inner ends of the jaws 76 which are designed to engage the edges of the blocks of wood are preferably inclined outwardly and downwardly, as 50 shown at 79, leaving the upper edges thereof comparatively sharp. Thus, as said clamps are set up, the tendency of the jaws 76 to move downwardly will operate in an obvious manner to draw the block engaged thereby 55 into firm engagement with the surface of the carriage B. Preferably, also, the normal position of the jaws 76 is such that they will engage the edges of the blocks as closely as practicable to the upper edges of said blocks 60 and still permit said clamps to pass beneath the cutter D. With this relation, it is obvious, that the pressure of said clamps, being applied above the central line of the thickness thereof, will tend to spring said blocks

downwardly at their centers into contact 65 with the bed of the carriage B.

Our improved pressure device for applying pressure to the blocks F as they are presented to the cutter D, in order to force the same down upon the carriage and to cause 70 their under surfaces to conform to the dish thereof, is as follows:—

Revolubly supported above the carriage B is a series of rollers 80, said rollers being arranged transversely of the machine substantially on the arc of a circle concentric with the cutter D and as closely adjacent as practicable to said cutter, in order that the pressure may be applied to said blocks as close as possible to the points where the blocks F are 80 presented to the cutter D.

In the preferable construction shown, the rollers 80 are supported in a frame 81 which extends over the carriage B. Said frame 81 is supported upon brackets 82 and 83 secured 85 to the frame or bed A of the machine and which extend upwards into proper position. Said frame 81 may be secured to said brackets 82 and 83 in any desired manner. In the preferable construction shown, said frame is 90 hinged to one of said brackets, as shown the bracket 82, and is adapted to be rigidly secured to the bracket 83 by means of eye bolts 84 pivoted to the bracket 83 and adapted to be swung into engagement with suitable slots 95 in the end of said frame, nuts threaded to the ends of said eye bolts providing means for clamping said frame to said bracket 83. With this construction, provision is made for disengaging said frame 81 from the bracket 100 83 and swinging the same up to the position shown in Fig. 1, thus rendering the parts beneath and at the under side of said frame accessible.

The rollers 80 are mounted in the frame 81 105 so as to exert a desired pressure on the blocks F supported on the carriage B of the machine, in the following manner:—

Secured in the frame 81 are sleeves 85 fitted to which, so as to be movable lengthwise therein, are rods 86 provided with lugs 87 at their lower ends which project below the sleeves 85 and in which the rollers 80 are mounted by means of pins 88.

The rods 86 and with them the rollers 80 115 carried thereby are held yieldingly toward the carriage B by means of suitable springs applied thereto, as shown, by coil springs 89 inserted between the bottoms of holes or recesses 90 formed in the upper ends of the 120 rods 86 and the inner ends of sleeves or bushings 91 threaded through caps 92 secured to the upper ends of the sleeves 85. By screwing the sleeves or bushings 91 in or out, the tension of the springs 89 may be increased 125 or decreased, thus providing means for regulating the pressure of the rollers 80.

The approach of the rollers 80 to the car-

riage B is limited by means of rods 93 threaded into the rods 86, said rods 93, as shown, being threaded into the bottoms of the holes or recesses 90 which receive the coil springs

5 89. The upper ends of the rods 93 project above the sleeves or bushings 91 and threaded thereto are nuts 94, contact of which with the upper ends of the sleeves or bushings 91 will operate, in an obvious manner, to limit 10 the downward movement of the rollers 80 under the influence of the springs 89. Also, by screwing said nuts 94 up or down on the rods 93, the extreme depressed positions of the rollers 80 can be conveniently adjusted.

15 As preferably constructed, the threads on the sleeves or bushings 91 and on the rods 93 and nuts 94 are of the same pitch, say ten threads to the inch. Thus, by turning the bushings 91 and the nuts 94 the same distance 20 in the same direction, the tension of the springs 89 may be adjusted without varying the adjustment of the pressure rollers 80 relatively to the carriage.

Set screws 95, threaded through the caps 25 92 are provided to secure the sleeves or bushings 91 in adjusted positions. Means are also provided for securing the nuts 94 in fixed relation to the sleeves or bushings 91, consisting, as shown, of pins 96 adapted to be 30 inserted through registering holes in the nuts 94 and in flanges formed on the upper ends of the sleeves or bushings 91.

In case it is desired to vary the extreme 35 depressed positions of any of the pressure rollers 80, this can be effected by removing the pin 96 of the pressure device, which it is desired to vary, and turning the nut 94 thereof either up or down, as it is desired to lower or raise said pressure roller.

40 Our improved pressure device also comprises means whereby the pressure rollers 80 may be independently raised and secured in raised positions, so that they will not bear upon the blocks F as said blocks pass beneath 45 them. The means for this purpose, see particularly Figs. 5 to 8, consist of levers 97, yokes 98 on the ends of which embrace flattened surfaces 99 on the nuts 94, said yokes being pivoted to said nuts at a distance 50 from their outer ends greater than the distance from their pivotal points to the lower sides of said nuts, equal to the distance which it is desired to raise said pressure rollers 80.

The ends of the yokes 98 bear upon the 55 upper surfaces of the flanges on the sleeves or bushings 91, so that, by turning said levers 97 into vertical position, as best shown in Fig. 7, the nuts 94 and with them, through their described connections therewith, the 60 pressure rollers 80 may be raised out of operative position. The yokes 98 are narrower than the thickness of the nuts 94, so that when the levers 97 are turned into horizontal positions, as best shown in Fig. 6, the nuts 94

will rest in contact with the upper ends of 65 the sleeves or bushings 91, thus permitting the pressure rollers 80 to assume their operative positions.

The rods 86 are secured against rotation in the sleeves 85, with the pressure rollers 80 in 70 alinement with the direction of movement of the carriage B in any suitable manner, as shown, by screws 100 threaded through said sleeves, the inner ends 101 of which are turned down to form pins and which project 75 into slots 102 formed in the rods 86. Being arranged on the arc of a circle, it is obvious that, to bring the different pressure rollers 80 in alinement with the direction of movement of the carriage, it will be necessary to form 80 the slots or grooves 102 at different points circumferential of the rods 86.

As shown, the sleeves 85 are secured in the frame 81 in the following manner:—Formed on the sleeves 85 adjacent to their lower ends 85 are flanges 103, 104, which are adapted to embrace the edges of a slot 105 formed in the frame 81, the edges of said slot 105 bearing against the sides of the sleeves 85 at the bottoms of the grooves formed by said flanges 90 103, 104, and the bearing surfaces on said sleeves being of considerable length to prevent turning of said sleeves in said slot. To provide for assembling said sleeves 85 in the frame 81, said frame is made in two separate 95 sections secured together by means of bolts 106, the slot 105 being formed partly in one section and partly in the other, so that by separating the sections of said frame, the slot 105 will be opened to permit the insertion or removal of the sleeves 85.

By making the slot 105 slightly narrower, when completely closed, than the dimension of the sleeves 85 at the bottom of the grooves formed by the flanges 103, 104, 105 it is obvious that said sleeves will be clamped between the edges of the slots 105 formed in different sections of the frame 81, thus providing convenient means for securing them in adjusted position.

With the described construction, it is obvious that the pressure rollers will be independent of each other both as regards operation and adjustment.

We claim:—

1. In a machine of the type described, the combination of a carriage the surface of which is dished transversely and a cutter revolvably mounted above said carriage, said cutter being set with its front side lower than 120 its rear side.

2. In a machine of the type described, the combination of a carriage the surface of which is dished transversely, a cutter revolvably mounted above said carriage, said cutter being 125 set with its front side lower than its rear side, and a pressure device adapted to apply pressure to the work supported on said carriage.

3. In a machine of the type described, the combination of a carriage the surface of which is dished transversely, a cutter revolvably mounted above said carriage, said cutter being set with its front side lower than its rear side, and a pressure device for applying pressure to the work supported on the carriage, said pressure device comprising a series of pressure rollers mounted substantially on the arc of a circle concentric with the cutter and closely adjacent to the front side thereof.

4. In a machine of the type described, the combination of a carriage the surface of which is dished transversely, a cutter revolvably mounted above said carriage, said cutter being set with its front side lower than its rear side, and a pressure device adapted to apply pressure to the work supported on the carriage, said pressure device comprising a series of independently supported rollers mounted substantially on the arc of a circle concentric with the cutter and closely adjacent to the front side thereof.

25 5. In a machine of the type described, the combination of a carriage the surface of which is dished transversely, a cutter revolvably mounted above said carriage, said cutter being set with its front side lower than its rear side, and a pressure device adapted to apply pressure to the work supported on the carriage, said pressure device comprising a series of independently supported rollers mounted substantially on the arc of a circle concentric with the cutter and closely adjacent to the front side thereof, and means for independently adjusting the pressure of said rollers.

40 6. In a machine of the type described, the combination of a carriage the surface of which is dished transversely, a cutter revolvably mounted above said carriage, said cutter being set with its front side lower than its rear side and means for adjusting the set 45 of said cutter to vary the height of the front side thereof relatively to its rear side.

7. In a machine of the type described, the combination of a carriage, a cutter revolvably mounted above said carriage and a pressure device, said pressure device comprising a series of pressure rollers mounted substantially on the arc of a circle concentric with said cutter and closely adjacent to the front side thereof.

55 8. In a machine of the type described, the combination of a carriage, a cutter revolvably mounted above said carriage and a pressure device, said pressure device comprising a series of independent pressure rollers mounted 60 substantially on the arc of a circle concentric with said cutter and closely adjacent to the front side thereof.

9. In a machine of the type described, the

combination of a carriage, a cutter revolvably mounted above said carriage and a pressure device comprising a series of independent pressure rollers mounted substantially on the arc of a circle concentric with said cutter and closely adjacent to the front side thereof, and means for independently adjusting the pressure of said rollers.

10. In a machine of the type described, the combination of a carriage, a cutter revolvably mounted above said carriage, a pressure device comprising a series of independent pressure rollers mounted substantially on the arc of a circle concentric with said cutter and closely adjacent to the front side thereof, and means for separately moving said rollers into and supporting them in inoperative positions.

11. A rotary disk planer comprising a fixed bed and supports therefor comprising a leg comprising a section secured to the bed and a base plate, the lower end of the leg section secured to the bed being rounded and engaging a corresponding recess in said base plate.

12. A rotary disk planer comprising a fixed bed and supports therefor comprising a leg comprising a section secured to the bed and a base plate, the lower end of the leg section secured to the bed being rounded and engaging a corresponding recess in said base plate, the recess in said base plate being of greater radius than the rounded end of said leg section secured to the bed.

13. A rotary disk planer comprising a fixed bed and supports therefor comprising a leg comprising a section secured to the bed and a base plate, the lower end of the leg section secured to the bed being rounded and engaging a corresponding recess in said base plate and means for flexibly connecting the sections of said leg to each other.

14. A rotary disk planer comprising a fixed bed and supports therefor comprising a leg comprising a section secured to the bed and a base plate, the lower end of the leg section secured to the bed being rounded and engaging a corresponding recess in said base plate, and means for flexibly connecting the sections of said leg to each other, said means comprising a bolt which extends through suitable holes in the sections of said leg, a nut threaded thereto and a spring inserted between said nut and one of said connected members.

15. In a machine of the type described, the combination with a carriage provided with guide slots, of clamps adjustably secured in said slots, said clamps comprising portions which project above the surface of said carriage provided with guide ways which are outwardly and downwardly inclined, jaws, flanges thereon fitted to and movable towards and from the surface of the carriage in said inclined guide ways, springs applied to said

jaws arranged to maintain them at the limit of their movement above the surface of the carriage, stops which limit the movement of said jaws under the influence of said springs, 5 and means for adjusting said clamps in the guide slots in said carriage.

In testimony, that we claim the foregoing as our invention, we affix our signatures in

presence of two subscribing witnesses this 30 day of January, A. D. 1907.
